ATTORNEY

UNITED STATES PATENT OFFICE.

FRANK W. BEBERDICK, OF WEST HOBOKEN, NEW JERSEY.

DESIGN FOR A COAT-PATTERN.

SPECIFICATION forming part of Design No. 30,220, dated February 14, 1899.

Application filed November 29, 1898. Serial No. 697,797. Term of patent 14 years.

To all whom it may concern:

Be it known that I, FRANK W. BEBERDICK, a citizen of the United States, residing at West Hoboken, in the county of Hudson and State 5 of New Jersey, have invented and produced a new and original Design for a Coat-Pattern, of which the following is a specification, reference being had to the accompanying drawing, forming part thereof.

10 The drawing represents in plan view a pattern of one side and half of the back of the coat, showing my new design, and it will be understood that the other side and half of the back are the same.

15 As shown in the drawing, the leading or material feature of my design consists in the part A, forming one side and half the front and half of the back, and in the particular shape or contour given to the upper edge or 20 ends of these parts. From the point a the edge of the part A extends downwardly on a straight line, and from the same point a the said edge extends upwardly and inwardly on a straight line to the point a' , from whence 25 the edge curves upwardly to the point a^2 .

From the point a^2 the edge of the part A extends on a downward and then upward curve to the point a^4 , forming the compound-curved line a^3 , which represents the shoulder line or 30 seam. The point a^4 is located below the point a^2 and slightly above the point a . From the point a^4 the edge of the part A extends downwardly and inwardly on a curve deviating 35 only slightly from a straight line to the point a^5 , from which point the said edge is curved in a small semicircle to the point a^6 . From the point b^8 the edge of the part B extends upwardly, curving first inwardly and then extending in an inclined substantially straight 40 line to the point b , which is opposite but slightly below the point a^4 of the part A and is separated therefrom by a narrow space b^9 .

From the point b the edge of the part B extends upwardly in a straight but sharply-inclined line to the point b^2 , thus giving the 45 shape of an obtuse angle to the point b . From the point b^2 the edge of the part B extends upwardly on an inward curve to the point b^3 , from which point the said edge extends horizontally on a slight downward curve 50 to the point b^4 , from whence the edge extends downward to the bottom of the part B. From the point d of the part D the edge extends upwardly and inwardly on a curved line to the point d' , from which point the said edge 55 extends inwardly to the point d^2 , and then outwardly to the point d^3 , forming a notch d^4 . From the point d^3 the edge extends upwardly on a compound-curved line to the point d^5 , and from thence downwardly to the point d^6 . 60 From the point d^6 the edge extends downwardly on a curved line to the point d^7 , from whence the said edge extends in a straight but sharply-inclined line to the point d .

By reason of the curvatures of the lines d 65 d^7 d^6 and a a' a^2 the edges of the parts A and D are separated, forming the space D'.

The point d^6 is on the same horizontal plane as the point b^3 , while the point d^5 is located above the horizontal plane of the said point b^3 . 70

Having fully described my invention, I claim as new and desire to secure by Letters Patent—

The design for a coat-pattern as herein 75 shown and described.

In testimony that I claim the foregoing as my invention I have signed my name, in presence of the subscribing witnesses, this 23d day of November, 1898.

FRANK W. BEBERDICK.
